UNITED STATES PATENT OFFICE.

ARTHUR C. DAVIDSON, OF CHICAGO, ILLINOIS.

DRAFT GEAR.

1,410,736.

Specification of Letters Patent. Patented Mar. 28, 1922.

Application filed May 7, 1920. Serial No. 379,572.

To all whom it may concern:

Be it known that I, ARTHUR C. DAVIDSON, a citizen of the United States, residing at Chicago, in the county of Cook and State of Illinois, have invented a new and useful Improvement in Draft Gears, of which the following is a specification.

This invention pertains particularly to draft-gears of the type utilizing both spring 10 pressure and friction in the buffing and pulling operations.

The primary object of the invention is to provide an improved construction which is strong and durable and which is capable of 15 utilizing, in as high a degree as possible, the compressive action of a spring or springs and the maximum frictional resistance which can be attained in a device of this character.

20 A further object is to provide a simple construction involving few parts, which can be readily assembled.

The invention is illustrated in its preferred embodiment in the accompanying 25 drawings, in which—

Fig. 1 represents a broken plan view, partly in section, of the improved draft-gear and the sub-structure of a car on which same is mounted; Fig. 2, a central vertical 30 longitudinal sectional view of the same, the yoke embracing the draft-gear being shown in elevation, however, and the draw-bar being omitted; Fig. 3, an enlarged broken longitudinal section of the draft-gear; Fig. 35 4, a transverse section on an enlarged scale, taken as indicated at line 4 of Fig. 2; Fig. 5, an inner perspective view of one of the friction shoes employed; and Fig. 6, a broken 40 transverse vertical sectional view taken as indicated at line 6 of Fig. 3.

In the construction illustrated, A, A' represent longitudinal frame members constituting a part of the substructure of a car-body; A², a transverse plate connecting said 45 members at their lower portions; A³, a plate forming a covering above the space between the members A, A'; A⁴, a pair of front stops for the draft-gear, said stops being secured to the inner sides of the longitudinal members A, A'; A⁵, a pair of rear stops for the 50 draft-gear, similarly secured to the members A, A'; B, B', front and rear follower plates, or stops, which engage, respectively, the front and rear stops; C, the improved 55 draft-gear interposed between the follower

plates; D, a longitudinal yoke embracing the follower plates and the interposed draft-gear; and D', a draw-bar equipped near its rear end with a transverse pin D² which extends freely through a slot 1 in the fur- 60 cated front end of the yoke and works freely in guide-slots 2 with which the frame members A, A' are provided.

The construction providing for the mounting of the draft-gear and the connection 65 thereof with the draw-bar may be any desired construction. In the form shown, the yoke D is provided at its front end with furcations 1^a through which the transverse slot 1 extends. The yoke D has an upper 70 longitudinal member 1^b, a lower longitudinal member 1^c, a front wall or shoulder 1^d which engages the front follower, and a rear wall or shoulder 1^e which engages the rear follower. 75

The draft gear C comprises an elongated inner spring casing C'; an elongated outer casing C² which freely receives the inner casing telescopically; a plurality of elongated segmental friction shoes C³ interposed 80 between the two casings; a heavy service spring C⁴ within the inner casing and adapted to exert force tending to move the inner casing in one direction and the friction shoes in the opposite direction; and a smaller 85 restoration spring C⁵ interposed between the front end of the inner casing C' and the rear end of the outer casing C².

In the illustration given, the casing members mentioned are of circular cross-section. 90 The inner casing member C' preferably comprises a cylindrical member which, in the illustration given, tapers very gradually from the front end to the rear end, the rear end being of a little less diameter than the 95 front end; and said member C' is provided at its front end with an inturned flange or wall 3 which affords a shoulder for the coil springs C⁴ and C⁵ to bear against.

The outer casing C² preferably comprises 100 a strong cast steel cylinder provided at its rear end with an inturned flange or wall 4 which bears against the follower B'. The segmental shoes C³ which are interposed between the two cylinders are shown as six 105 in number. They substantially fill the space between the two cylinders, but are separated at their edges by small spaces 5. Each friction shoe preferably comprises an elongated segmental member extending approximately 110

the full length of the cylinders. Each of these shoes is provided with a plurality of cams or wedges 6, formed integrally with the shoe. In the illustration given, these 5 wedges are formed on the exterior surfaces of the shoes; and the interior surface of the outer cylinder C² is provided with circumferential recesses 7 which accommodate the wedges. The wedges 6 are provided with 10 taper surfaces 6^a of gradual inclination which engage corresponding taper surfaces with which the annular recesses 7 are provided. The wedge surfaces preferably form small angles with a horizontal line, the taper 15 being small. Again, the left-hand end of the inner cylinder C' is slightly greater than the right-hand end, as viewed in Fig. 2, so that the inner cylinder has a very slight taper. The length of the frictional engagement 20 between the inner cylinder and the shoes under compression, preferably is at least twice the diameter of the inner cylinder.

The shoes C³ are provided at their rear 25 ends with the inturned flanges 8. These flanges or lips encircle a ring 9 which has an outturned flange 9^a which engages the inner surfaces of the lips. This ring affords a bearing for the rear end of the heavy 30 spring C⁴. Thus, the spring C⁴ tends to force the shoes rearwardly and hold the draft-gear in its extended condition.

The small inner coil spring C⁵ has its front end bearing against the shoulder 35 of the inner casing C' and has its rear end extending freely through the ring 9 and engaging the rear end or wall 4 of the outer casing C². The chief function of the spring C⁵ is to insure the return of the yoke and 40 draw-bar to the extended position, that is, the draw-bar is normally projected a certain distance in front of the end of the car; and it is desirable that the draw-bar shall be projected automatically immediately following 45 the buffing operation, in order that there may be no danger of sticking, with consequent danger of the draw-bar being suddenly projected when some person is standing near the car-coupling.

The draft-gear C, as a whole, is interposed 50 between the followers B and B' and within the yoke D. When the yoke is drawn forwardly the follower B remains stationary, of course, while the follower B' is caused to 55 exert pressure against the rear end of the outer casing member C². This operates through the wedges 6 to force the segmental shoes inwardly as well as longitudinally, and causes the shoes to exert exceedingly strong 60 gripping action upon the inner cylinder C', which, as stated, tapers gradually. Thus, an exceedingly strong resistance is offered to the forward movement of the outer cylinder and the shoes with relation to the inner cylinder by the intense friction created.

This frictional resistance is in addition to the resistance offered by the heavy coil spring C⁴ and the lighter coil spring C⁵.

In the buffing operation, the follower B' remains stationary, of course, while the follower B is forced rearwardly, thus forcing the inner cylinder C' rearwardly. The intense gripping action between the shoes and the inner cylinder occurs exactly as in the pulling operation. It may be noted here 70 that in the illustration given the rear end of the draw-bar D' abuts against the follower B, and the follower B extends freely through the front end of the yoke D.

It will be noted that the construction provides for the use of long coil springs; that the construction provides also for the use of friction surfaces of very large area; and that the construction provides further for a balanced pressure upon the shoes, tending 85 to cause the shoes to grip the inner cylinder uniformly at all points. This arises from the fact that each shoe is provided with a longitudinal series of wedges, which tend to cause the shoe to move in with a parallel 90 movement when the draft-gear is contracted. The improved construction provides for uniform wear of the parts and uniform radial pressure between the shoes and the casing-members. Substantially uniform radial 95 pressure is exerted between the inner cylinder and shoes at all points on the outer surface of the inner cylinder.

The outer cylinder C² is shown provided near its ends with lateral flanges 10 which 100 serve as spacing members between said cylinder and the longitudinal members A, A' of the car. The cylinder C² is also provided at its upper and lower sides with lugs or bearings 11 embraced by the upper and 105 lower members 1^b and 1^c of the yoke D. It will be understood that the device C, as a whole, may be reversed within the yoke D, if desired. It may be added that the improved construction utilizes frictional contact 110 substantially throughout the length of the cylinders in the buffing and pulling operations; also that the construction enables long coil springs to be utilized; also that the curved cross-section of the casings insures 115 great strength; and, finally, that the provision of a series of wedges on each segmental shoe and formed integrally therewith tends to simplicity of construction and increased strength, and provides for a uniform contraction of the shoes upon the inner cylinder during the contraction of the draft gear under either pulling or buffing stress.

The foregoing detailed description has 125 been given for clearness of understanding only and no unnecessary limitation should be understood therefrom, but the appended claims should be construed as broadly as permissible in view of the prior art.

What I regard as new and desire to secure by Letters Patent is—

1. In a draft-gear, the combination of an elongated hollow inner spring-casing open at one end and provided with an abutment at the other end, an elongated hollow outer casing telescopically receiving said inner casing, elongated shoes interposed between said casings and each provided with a plurality of integral wedge-surfaces disposed at intervals throughout its length coacting with a plurality of integral wedge-surfaces with which one of said casings is provided, said shoes being provided at one end with 15 inturned lips, opposite said abutment, and a spring in said inner casing disposed between said abutment and said inturned lips and serving to force said shoes and inner casing in opposite directions.
2. In a draft-gear, the combination with the sub-structure of a car-body provided with sets of stops, a draw-bar and a suitable yoke connected therewith, of a device mounted in said yoke comprising an inner 25 spring-casing, an outer casing telescopically receiving the inner casing and provided interiorly at intervals throughout its length with a series of recesses having inclined walls, a plurality of elongated friction 30 shoes interposed between said casings, each shoe having a series of integral projections corresponding with and received by said recesses, said projections having inclined surfaces co-acting with said first-named surfaces, a spring within said inner casing having one end bearing against one end thereof and having the opposite end engaging inturned lips with which the opposite ends of said shoes are provided, and means for 35 transmitting pressure from the inner casing to one set of said stops and from the outer casing to the other set of said stops.
3. In a draft-gear, the combination of an elongated hollow inner spring-casing having a gradual external taper and having an abutment at its large end, an elongated hollow outer casing telescopically receiving said inner casing, elongated shoes interposed between said casings and each provided with a plurality of integral wedge-surfaces disposed at intervals throughout its length and co-acting with corresponding integral wedge-surfaces with which the outer casing is provided internally and each provided, also at the end remote from said abutment with an inturned lip, and a spring in said inner casing confined between said abutment and said inturned lips and serving to force said shoes and inner casing in opposite directions.
4. In a draft-gear, the combination of an elongated hollow inner spring-casing provided at one end with an abutment, an elongated hollow outer casing telescopically receiving said inner casing and provided throughout its length interiorly with a series of spaced circumferential recesses having wedge-surfaces, a plurality of elongated shoes interposed between said casings and each provided with a series of external integral projections corresponding with said recesses and having wedge-surfaces co-acting with said first-named wedge-surfaces and each provided with an abutment at the end remote from said first-named abutment, and a spring in said inner casing confined between the abutment of the inner casing and the abutments of said shoes.
5. In a draft-gear, the combination with the sub-structure of a car-body provided with sets of stops, a draw-bar and a suitable yoke connected therewith, of an elongated tapered cylindrical inner spring-casing open at the small end and provided with an end wall at the large end, an elongated cylindrical outer casing telescopically receiving said inner casing and provided with a closed end and having interiorly and substantially throughout its length a series of annular recesses provided with wedge-surfaces, a plurality of transversely curved segmental friction shoes interposed between said cylinders and having inturned lips at their ends remote from the end wall of the inner casing, each of said shoes being provided on its convex surface with a series of segmental projections having wedge-surfaces co-acting with said first-named wedge-surfaces, a heavy coil spring interposed between the end wall of said inner casing and the in-turned lips of said shoes, and a smaller coil spring interposed between the end wall of said inner casing and the closed end of said outer casing.

ARTHUR C. DAVIDSON.
